UNITED STATES PATENT OFFICE.

DANIEL TAGGART, OF INDIANAPOLIS, INDIANA.

BOILER-FURNACE.

No. 891,641.

Specification of Letters Patent.

Patented June 23, 1908.

Application filed September 20, 1907. Serial No. 393,755.

To all whom it may concern:

Be it known that I, DANIEL TAGGART, a citizen of the United States, residing at Indianapolis, in the county of Marion and 5 State of Indiana, have invented certain new and useful Improvements in Boiler - Furnaces; and I do declare the following to be a full, clear, and exact description of the invention, reference being had to the accompanying drawings, and to the letters and figures of reference marked thereon, which form a part of this specification.

This invention relates to furnaces in which it is designed to consume fuel for the purpose 15 of utilizing the heat of combustion, and the invention has reference more particularly to boiler furnaces, the object of the invention being to provide an improved construction in furnaces to the end that economy in the 20 consumption of fuel may be attained, and that the smoke nuisance in a measure be eliminated by preventing the emission of the products of imperfect combustion from the furnaces.

25 The invention consists in an improved furnace comprising a combustion chamber having grate-bars in a relatively small portion of the floor thereof, and a relatively small draft passage in a wall of the combustion chamber remote from the grates; and the invention consists further in the novel construction, and the parts and combinations and arrangements of parts as hereininafter particularly described and defined in 30 the appended claims.

Referring to the drawings, in which similar reference characters designate like elements or features of construction, Figure 1 is a side elevation of an improved boiler furnace constructed substantially in accordance with the invention, a portion of the furnace wall being broken away and exposing a boiler mounted therein; Fig. 2, a horizontal sectional view approximately on the line A A in Fig. 1; 40 Fig. 3, a transverse sectional view approximately on the line B B in Fig. 1, looking rearward; and Fig. 4, a transverse sectional view on the line C C in Fig. 1, looking forward; the line D D in Fig. 3 indicating approximately the plane on which sectional portions of Fig. 1 appear.

In constructing the improved furnace, the

walls thereof may be variously arranged and the heat from the furnace may be utilized in various ways, in some cases it being desirable 55 to construct an artificial roof for the furnace, but in the present case and when the furnace is constructed for heating boilers, the boiler conveniently serves as the roof for the combustion chamber while permitting of the application of the heat directly to the boiler. Of course it will be understood that various types of boilers may be used with the improved furnace.

In the drawings *a* and *a'* designate the two 65 side walls of the furnace; *b*, the front wall; and *b'* the metallic boiler front; and *c*, the rear wall of the furnace. A boiler *d* having a steam dome *d'* is mounted on the front wall between the side walls and extends 70 rearward nearly to the rear wall *c* and has a smoke box *e* on which is a chimney *f*. The boiler is of suitable diameter so as to extend across from either side wall to the other one, and is arranged at a suitable height so as to 75 afford space beneath the boiler for the combustion chamber and heat passages.

The combustion chamber, formed partially by the side walls and the front wall, has a flat floor *g* extending from one side wall 80 to the other one, and from the front wall rearward relatively a long distance toward the rear end of the boiler and at a suitable distance below the boiler, the floor being preferably composed of fire bricks and suitably supported as by earth, and in one portion of the floor is an opening *g'* adjacent to one side wall and the front wall, there being an ash pit extending from the opening downward a suitable distance and having a side 90 wall *h* and an end wall *h'* forming ash pit walls, opposite ash pit walls being formed by portions of the adjacent side wall and the front wall. A suitable number of grate-bars *i* extend across the opening *g'* for supporting the fuel when coal or wood is used, and the front wall has a fire door frame *j* in one end thereof so as to be directly in front of the group of grate-bars, a fire door *k* being mounted on the door frame. A suitable 95 number of air ducts *l* are arranged in the front wall between the door frame and the opposite end of the front wall, so that the atmospheric air may enter the combustion 100

chamber over the portion of the floor at one side of the fire grates. The front wall is provided with an ash pit door *m*.

A partition wall *n* is constructed at the rear end of the floor *g* and extends from either side wall *a* or *a'* to the other side wall and up to the boiler, and it has a draft passage *o* therein near the side wall adjacent to which the grate-bars are arranged and near the plane of the top of the floor *g*, the draft passage being rearward of and remote from the grate-bars. A deflector *p* is preferably arranged at a suitable distance from and opposite to the draft passage *o* at the rear of the wall *n* and extends a suitable distance from the adjacent side wall inward and up to the boiler for deflecting the heat towards the opposite side wall *a'*, there being a chamber or passage *q* extending from the wall *n* to the rear wall *c* of suitable depth for conveying the heat and gases of combustion under the rear end of the boiler and up to the boiler tubes or flues.

It will be understood that while it is designed to burn coal or wood, or coke, preferably bituminous coal, on the fire grates and that the fire grates may be suitably modified to suit the fuel, it is clear that oil or gas may be used as fuel if desired, and suitable modifications will be made with respect to admitting air through or between the fire grates and through the air ducts *l* to suit the characteristics of the fuel.

In practical use the fuel will be ignited on or immediately above the grate-bars *i* and the heat generated together with the chimney draft will cause the partially ignited carbon or gases of combustion to whirl or gyrate through the space in the combustion chamber towards all portions thereof away from the grate-bars, particularly towards the side wall opposite to which the grate-bars are arranged and to the front wall *b*, and also rearward and upward towards the boiler, the atmospheric air entering the air ducts providing oxygen which mixes with the gases, so as to make perfect combustion possible, the result being intense heat confined by the surrounding chamber walls, so that the heat will be in large volume immediately beneath the boiler, while the passage *o* will permit the heat to escape into the chamber *q* for heating the rear portion of the boiler and thence pass through the draft passages of the boiler towards the smoke box *e*. It will be seen that the passage *o* is proportioned relatively to the area of the fire grates, so that the draft passage will carry away conveniently the gases or fumes resulting from the burning of the fuel while the large area of the combustion chamber beyond the fire grates will at all times contain a relatively large volume of burning gases which will thoroughly con-

sume all the combustible matter derived from the fuel, with ample time for consumption of the products of combustion, and therefore the highest results will be attained.

Having thus described the invention, what is claimed as new is—

1. A furnace comprising two opposite side walls, a front wall with a fire-door, a substantially flat floor extending from the front wall and from one to the other of the side walls and having a relatively small draft opening therein remote from one of the side walls and adjacent to the front wall and the opposite side wall, a rear wall at the rear end of the floor and opposite to the front wall and extending from one to the other of the side walls with a roof joined to all the walls, the rear wall having a draft passage therein adjacent to the floor and one of the side walls and remote from the other side wall and the roof.

2. A boiler furnace comprising a front wall, two opposite side walls joined to the front wall, the front wall having a door adjacent to one and remote from the other one of the side walls, a rear wall joined to the side walls, a boiler extending from the front wall nearly to the rear wall and joined to the side walls, a substantially flat floor extending from the front wall rearward and from one to the other of the side walls below the boiler and having a relatively small opening therein remote from one of the side walls and adjacent to the opposite side wall and the door of the front wall, grate-bars extending across the opening, and a partition wall at the rear end of the floor and extending therefrom up to the boiler and from one to the other side wall, the partition wall having a draft passage therein adjacent to the floor and also to the side wall that is adjacent to the opening of the floor, the passage being remote from the opposite side wall and the boiler.

3. A boiler furnace comprising a front wall, two side walls joined to the front wall, the front wall having a door adjacent to one and remote from the other one of the side walls and having also air-ducts therein adjacent to the said last-mentioned side wall, a rear wall joined to the side walls, a boiler extending from the front wall nearly to the rear wall and joined to the side walls, a floor extending from the front wall rearward and from one to the other of the side walls below the boiler and having an opening therein remote from one of the side walls and adjacent to the opposite side wall and the door of the front wall, grate-bars extending across the opening, a partition wall at the rear end of the floor and extending therefrom up to the boiler and from one to the other side wall, the partition wall having a draft passage therein adjacent to the floor and also to the side wall that is

adjacent to the opening of the floor, the
passage being remote from the opposite side
wall and the boiler, and a deflector extending
from the side wall that is adjacent to the
5 opening of the floor past the draft passage
towards the opposite side wall and up to-
wards the boiler.

In testimony whereof, I affix my signature
in presence of two witnesses.

DANIEL TAGGART.
